UNITED STATES PATENT OFFICE.

THOMAS H. BREWER AND ORA A. BREWER, OF PAWNEE ROCK, KANSAS.

WINDMILL.

SPECIFICATION forming part of Letters Patent No. 380,547, dated April 3, 1888.

Application filed June 16, 1887. Serial No. 241,512. (No model.)

To all whom it may concern:

Be it known that we, THOMAS H. BREWER and ORA A. BREWER, citizens of the United States of America, residing at Pawnee Rock, 5 in the county of Barton and State of Kansas, have invented certain new and useful Improvements in Windmills; and we do hereby declare the following to be a full, clear, and exact description of the invention, such as will enable 10 others skilled in the art to which it appertains to make and use the same, reference being had to the accompanying drawings, and to letters or figures of reference marked thereon, which form a part of this specification.

15 Our invention relates to certain new and useful improvements in windmills, the object of our invention being to provide an improved construction, whereby the parts are rendered much more rigid and simple than has heretofore been accomplished; also, to provide a 20 cheap and effective means for throwing a windmill in and out of the wind.

With the above leading objects in view our invention consists in the construction and combination of the parts, as will be hereinafter 25 fully set forth, and specifically pointed out in the claim.

In the accompanying drawings, which illustrate our invention, Figure 1 is a side view of 30 a windmill constructed in accordance with our improvement. Fig. 2 is a detail front view. Fig. 3 is a detail perspective view, and Fig. 4 is a detail plan view.

In the accompanying drawings, A refers to 35 the tower or windmill support, which is of ordinary construction, the same being provided near its top with a cross-beam, a, which forms a support or bearing for a stationary shaft, B, which extends upwardly therefrom 40 and passes through a socket, B', which is attached to the upper end of the frame or support A by a flange, b, which is formed thereon, said flange forming the under bearing for the yoke. This stationary shaft B is tubular, and 45 its upper end enters a socket in the upper transverse portion of the yoke, thereby forming a support or bearing upon which the yoke can turn.

The yoke C is preferably made of a single 50 casting of the shape shown, and it is provided

through its horizontal lower portion, C', with a perforation, through which the stationary shaft B, which is tubular, passes, and on a line with the opening the upper horizontal portion, c, has a shoulder, upon which shoulder the upper end of the shaft B will rest, a similar opening being formed therein immediately above the same. By this construction the yoke will be held in its proper position, and the shoulder hereinbefore referred to will form a bearing upon which the yoke may turn.

The front vertical bar of the yoke C is provided with a horizontal opening, through which the shaft D of the windmill passes, and adjacent to the perforation through which the shaft passes the lower portion of the journal-box d is formed integral with the yoke, while the upper portion, d', which is provided with an oil-cup, is bolted thereto in the usual manner.

The shaft D has rigidly attached thereto a wind-wheel, E, which consists of a series of radiating arms, e, which are attached by suitable bolts to a casting, F, which is rigidly attached to the shaft D, hereinbefore referred to. 75 To the radiating arms e are secured circles f, to which the stationary blades F' are attached. The radiating arms e are provided with bent bars g, as shown in Figs. 1 and 2, which bars are connected by short eyebolts g' and a disk, 80 h, attached to the end of the shaft D, whereby the radiating arms are braced. The aforesaid braces may be tightened by simply turning the nuts attached to the eyebolts which pass through the disks, or by moving the disk having the radiating arms rearwardly upon the shaft D.

The end of the shaft D which projects through the yoke C is provided with a crank-wheel, I, to which the bent pitman J is pivotally attached, the upper end of said pitman being bifurcated and pivotally attached to the pump-rod K. The pump-rod K passes through the upper transverse portion of the bracket L, which is rigidly attached to the upper portion 95 of the yoke.

The yoke C is provided at one side of its front vertical portion with a vane-head, M, which consists of lateral projecting portions m m, which are perforated at their outer ends

for the reception of a pivot-pin which passes through straps n and n' , attached to the center bar, N , of the vane. The upper bar, n , at a suitable point is bent so as to provide a recessed portion and bearings for a pulley, o , which travels upon a guide, O . This guide preferably consists of a bar of metal, which is attached to the front portion of the yoke above the bearing of the shaft D , from which it extends downwardly parallel with the wheel and is bent upon a segment of a circle to the opposite side or rear portion of the yoke C , to which it is rigidly secured. This guide-bar O is provided with rubber stops p and p' , against which the center bar, N , of the vane will abut when it reaches the limit of its movement in either direction.

Q refers to a bent lever which is pivotally attached to the rear side of the yoke, the upper portion of this lever being connected by a rod, R , to the center rod, N , of the vane. The lower end of the lever Q is provided with a suitable weight, which is adjustable thereon, and adjacent to the normal position of said weight an eye is formed, within which eye can be attached a cord, S , which extends from said eye to the upper portion of the yoke, where it passes over a pulley, s , which is pivotally mounted upon the upper portion of the yoke. The cord is then let down through the stationary shaft B to a point near the lower portion of the frame. When said cord is slack, the weight will hold the vane in a position substantially at right angles with the wheel, so as to hold the same in an operative position, and when it is desired to throw the wheel out of an operative position, by simply drawing upon the cord the weighted end of the le-

ver will be elevated and the vane will be swung upon its pivot, so as to be parallel with the wheel.

We are aware that prior to our invention it has been proposed to operate the vane of a windmill by a cord or other suitable flexible connection, which is attached to a weighted lever, so as to swing said vane upon the yoke, and we do not claim such construction, broadly; but

What we claim as new, and desire to secure by Letters Patent, is—

The combination, substantially as before set forth, of the vertical tubular shaft B , a rectangular frame or yoke having upper and lower members provided centrally with bearings to receive said shaft, a front vertical member 55 provided at one side with a vane-head and centrally with a bearing for the wheel-shaft, and a rear vertical member carrying a pivot-stud, the vane pivoted to the vane-head, a guide-rod secured to the front and rear vertical members of the yoke, a guide-roll journaled on the vane and adapted to travel on the guide-rod, a weighted lever mounted on the pivot-stud of the rear vertical member, a rod connecting the upper end of said lever with the 65 vane, the wind-wheel journaled in its bearing, and a rope or cord connected to the lever to elevate the weighted end thereof.

In testimony whereof we affix our signatures in presence of two witnesses.

THOMAS H. BREWER.
